BUNDLE TYING MACHINE

Albert H. Saxton, Blissfield, Mich., assignor to
 National Bundle Tyer Company, Blissfield,
 Mich., a corporation of Michigan

Application September 3, 1943, Serial No. 501,105

8 Claims. (Cl. 289—1)

This invention relates to machines for wrapping and tying strings about bundles, and particularly to improvements in various features of such machines.

An objectionable feature in the use of machines of this character, wherein a rotary tying head is employed, is that, so far as I am aware, no efficient means has been provided to tighten the knot after disengagement from the tying head bill, thereby leaving a relatively loose knot and loose string on the bundle.

A primary object of the invention is to overcome this objection by the provision of simple and efficient means operating in connection with the tying head to tighten the knot as it is slipped off the bill of the tying head and while a looped portion of the string is still held by the jaws of the bill.

A further object of the invention resides in an improvement in the string clamping feature of the bill jaws of the tying head, whereby the bill remains in engagement with the looped portion of the string until after the forming and tightening of the tie has been completed and until the bill has moved back to a predetermined angle relative to the line of releasing pull on the engaged knot loop and a predetermined outward pulling force has been applied to the loop.

A further object of the invention is the provision of improved tension means for the string between the needle and source of supply, which means is normally active on the string during the major swinging movements of the needle to apply tension to the string to resist feed thereof, and is automatically actuated by the needle to release such tension when the needle is at the upper end portion of its stroke.

A further object of the invention is the provision of a needle arm that is longitudinally extensible radially of its swinging axis together with means for effecting a lengthening and shortening of the arm during predetermined portions of its swinging movements whereby the needle, when at its upper or at-rest position, will stand a greater height above the machine table than would be the case if the entire movement of the needle was concentric to its axis, thus providing greater room for the handling of bundles to be tied.

Other objects and advantages of the invention will be apparent from the following detailed description and from the accompanying drawings illustrating one embodiment of the improved machine, in which—

Figure 1 is a rear perspective elevation of a

machine embodying the invention, with the operating parts in at-rest position and with parts broken away; Figs. 2 and 3 are front and side views, respectively, thereof; Fig. 4 is a fragmentary perspective view of a portion of the machine, with parts broken away and showing the string knotting and locking means, with the former tilted rearwardly in knot-stripping position; Fig. 5 is a vertical cross-section on the line 5—5 in Fig. 7, with the parts in upright at-rest position; Fig. 5A is a fragmentary section on the line 5A—5A in Fig. 5; Fig. 6 is a similar view, with the knot tying means partially tilted to stripping position; Fig. 7 is a top plan view of the string tying and clutch mechanisms in the upright position shown in Fig. 5, with a portion of the frame broken away; Fig. 8 is a similar view of the tying mechanism in the partially tilted position shown in Fig. 6, showing a knot after being stripped from the tying head bill but not completely tightened; Fig. 9 is a front elevation of the string clutching and tying mechanisms in upright position, as shown in Fig. 7, and with parts broken away; Fig. 10 is a fragmentary front elevation of the knot tying and knot stripping parts in substantially the relative position shown in Fig. 8; Fig. 11 is a face view of the combination intermittent gear and cam for operating the string clutching and tying mechanisms; Fig. 12 is a perspective view of the string clutching and tying mechanisms, with a string engaged therewith preparatory to tying; Figs. 13, 14, 15 and 16 are perspective views of a tying head in tying engagement with a string and at different stages in the tying operation; Fig. 17 is a perspective view of a tying head after a knot has been formed therearound and at the initial stage of the knot stripping operation; Fig. 18 is a perspective view of a portion of the tying head and the stripper means showing a knot stripped from the head and in tightened position, with its loop still engaged by the jaws of the tying head, and Fig. 19 is a perspective view of a portion of the tying head and clutch and knife showing the strings severed and the knot formed.

Referring to the drawings, 1 designates the machine frame which supports a table 2 on which the bundles are placed during tying and has a side upright or housing 3 at the rear of the table, or at the side thereof opposed to that at which the operator stands.

In the base of the frame 1, from front to rear, is mounted a shaft 5 carrying a pulley 6 connected by a drive belt 7 to the small pulley 8 of a motor 9. Above the shaft 5 parallel therewith is

mounted a second shaft 10 having, in the present instance, a loose sprocket wheel 11 on its rear end within the lower portion of the housing or upright 3 and driven by a chain 12 from a much smaller sprocket wheel on the shaft 5. The shaft 10 carries at its front end a combination cam and intermittent gear 15 for actuating the knot tying and string clutching mechanisms, and rearwardly thereof carries a cam 16 which actuates the bundle holding means as hereinafter described.

String feeding means

The string 20 is supplied from a ball or other suitable source 21, mounted on a bracket 22 supported by the upright 3, and is fed by a needle 25 around a bundle through an opening in the table and to the clutching and tying mechanisms of the machine. The form and general operation of these parts and mechanisms is like or similar to those heretofore used, except as hereinafter described.

The rocker arm 26 for the needle is of right angular form and includes the radial inner end part 27 and the laterally projecting outer end part 28, by which latter the needle is carried. The radial part 27 fixedly projects from the forward end portion of a rock-shaft 29 mounted in the upright 3 above the table 2. A wheel 30, preferably of drum form, is fixed to the rear end of the shaft 29, and predetermined rocking movements are imparted thereto by reciprocatory movements of a pull chain or strap 31. This pull member is of endless form and extends over the wheel 30, being fixed thereto at 31^a, and under the idler 32, and is connected by a link 33 to the wrist pin of a crank 34 that is loosely mounted on the shaft 10 at the rear side of the sprocket wheel 11. A downstroke of the link 33 imparts a down or feeding movement to the needle and a return stroke is imparted thereto by a strap 35 which extends over the wheel 30, being fixed thereto at 35^a, and attaches at its free end to a retractile spring 35^b that is anchored to the frame part 3.

The sprocket wheel 11 fixedly carries a ratchet wheel 36 with which a pawl 37 on the crank-arm 34 is adapted to engage. This pawl is moved into engagement with the ratchet by a spring 38, and when the crank-arm is in its upright or at-rest position, as shown in Fig. 1, the nose of the pawl is engaged by a trip finger 40 which stands in its path of revoluble movement with the crank-arm and holds the pawl raised from engagement with the ratchet. The catch finger 40 is carried by a shift rod 41 and is movable by axial shifting movements of the rod into and out of register with the pawl end. The tripping movements of the rod 41 are effected by movements of the lever 42 which engages the free end of the rod and may be actuated in any suitable manner.

It is apparent that when the rod 41 is moved to the right (Fig. 1), it passes from under the pawl 37, permitting it to engage the rotating ratchet wheel 36 and turn the crank-arm 34. At the end of a complete revolution of the crank-arm the nose of the pawl 37 strikes the finger 40, which then stands in its path of movement, and releases the engagement of the pawl with the ratchet. During a downstroke of the crank-arm 34, the link 33 actuates the chain 31 to impart a down or string feeding stroke to the needle 25, and during an upstroke the spring 35^b acts to impart an upstroke to the needle.

A novel feature of the needle operating means

consists in making the radial part 27 of the rocker arm 26 of two-part telescoped form, so that it may be freely lengthened or shortened radially of its rocking axis and thus vary the radial distance of the horizontal part 28 of the rocker arm and the needle 25 from the rocking axis. To effect such action the outer section of the radial part 27 is provided with a roller 45 which, during swinging movements of the arm, travels in a camway 46. The lower portion of this way is concentric to the axis of the rock shaft 29, while its upper end terminating a greater distance from such axis than its lower end. This causes a lengthening of the radial arm part 27 as its roller 45 passes through the upper portion of the way, and effects a greater spacing of the needle and arm part 28 above the table 2 than would otherwise be the case, thus providing more free space above the table for the insertion of bundles to be tied.

The outer section of the radial arm 27 is provided with an angular bracing part 47 which slidably engages a laterally projecting part 48 on the inner section of the radial arm and prevents the horizontal arm 28 from turning relative to the arm 27.

Another novel feature of the string feeding means consists in the tensioning means for the string, which means is automatically operable to remove the tension from the string when the needle is in its upper at-rest position, and is automatically operable to engage and tension the string during the feed strokes of the needle.

The string 20 as it unwinds from the ball 21 passes, in the present instance, through guiding eyes 50, thence down along the frame part 51 between it and a spring-pressed clamping finger 52. The string thence loops outwardly through a guiding eye at the end of a spring finger 53 and back therefrom over the needle 25 lengthwise thereof through a series of guiding eyes thereon. The tension finger 52 is hinged at its upper end and is yieldingly held in clamping engagement with the string by a spring 54. A release lever 55 is fulcrumed to the frame 51 adjacent to the lower end of the tension finger 52 and has a substantially horizontally extending long arm a (Fig. 1), which rides over and is raised by the needle 25 as it nears and reaches its normally at-rest or starting position. The inner end of the lever 55 is provided with an upright finger b which, when the lever is rocked by engagement of the needle therewith, is caused to engage the adjacent free edge portion of the tension finger 52 and move it sufficiently to release its tension engagement with the string. It is thus apparent that when the needle is in its raised or at-rest position, it holds the lever 55 raised to release the tension of the finger 52 on the string, thereby enabling the string to be freely drawn out by a bundle when being positioned on the table for tying. It is also apparent that as soon as the needle has passed from under the arm a of the release lever 55, the tension finger will be permitted to engage the string and apply the desired tension thereto to suit the wrapping operation of the string around the bundle during a downward swinging movement of the needle.

String clutching or locking operation

Beneath the table 2 is located the string tying mechanism A and at its left the string clutching or locking mechanism B, as shown particu-

larly in Figs. 4, 7 and 9, and which in their general arrangement and operation, except for specific features hereinafter described, are well understood in the art. The purpose of the mechanism B is to clamp and hold the two ends of a string after it has been looped about a bundle and during a part of the string tying operation.

This clutching mechanism includes a pair of spaced string clamping fingers 60 (Figs. 4 and 9), which are vertically disposed and spaced at their upper ends by a companion clutch finger 61 that is mounted for rocking movements relative to the fingers 60 in the plane of their faces and has its inner arcuate edge slidable over the upper inner edge portions of the fingers 60 and also serving as a spacing means therefor. The fingers 60 have their upper ends curved so that they approach the finger 61 lengthwise thereof in curved or wedging relation. The lower or curved clamping surface of the finger 61 terminates at its free end in a downwardly extending shoulder or hook nose 62 which serves to draw an engaged string back between the clamping edges of the fingers 60 and the finger 61 when the latter is rearwardly rocked. A clamping tension is applied to the fingers 60 by a screw 63 and spring 64. The screw is projected through apertures in the fingers, into one of which it is threaded, and the spring is disposed between the other finger and the head of the screw.

The fingers 60 are supported at their upper ends by a stud 65 which fixedly projects from the upper end of a rocker frame 66 of the tying mechanism A and projects through vertical slots in the two fingers. The outer or left hand finger 60, in Fig. 9, has an outward side thrust against a stop washer 67 on the pin, while the outer or right side of the other finger 60 receives the thrust action of a coiled expansion spring 68 on the stud, which is adjustable as to tension by a nut 69.

During a tying action, it is necessary for the clutch means to yield in the direction of the knot in order to supply sufficient string for the knot, and this is accomplished by the clamping fingers 60 and 61 swinging as a unit toward the tying mechanism against the tension of the spring 68. To permit this movement of the clutch fingers, they are mounted at their inner or lower ends for rocking movements about the axis of a forwardly and rearwardly extending shaft 70. This shaft is carried by a rocker frame 71, which in turn is carried for forward and backward rocking movements, or in a direction at right angles to the axis of the shaft 70, by a stub shaft 72 (Fig. 9) that is journaled in a bearing 73 in the adjacent side of the rocker frame 66. A roller 74 is carried by the forward end of the shaft 70, and this roller engages an operating cam, as hereinafter described, to impart a predetermined rearward rocking movement to the frame 71 and clamping finger 61 at each bundle tying cycle. The fingers 60 have loose connection at their lower ends with the free end portion of the finger 61, so as to permit the fingers 60, due to their engagement with the stud 65, to be held against such rocking action.

In the operation of the clutch mechanism B the free or lower end of the string 20, when the feed needle is in the raised, at-rest or bundle-receiving position shown in Fig. 1, is disposed between the coating-edge portions of the fingers 60 and 61 and firmly clamped thereby. At such stage the fingers are in the relative clamping relation shown in Fig. 12, with the finger 61 in

its forward position relative to the fingers 60. The clamped string extends from the clutch mechanism to the right under the bill of the tying mechanism A, as hereinafter described, and thence up to the needle 25, as indicated in Fig. 1.

A bundle, when placed on the table 2 preparatory to being tied, is moved to the left against the depending string 26, which is clamped at its lower end by the mechanism B, such movement of the bundle continuing until it has looped the string about the left side and bottom of the bundle, and the right hand side of the bundle is substantially in vertical register with the tying head of the mechanism A. When a bundle tying cycle of the machine is started, the feed needle is caused to swing downward around the bundle and under the knotter bill and the forwardly projecting end of the clutch finger 61, thus placing the downwardly swung portion of the string in substantially the relationship to the bundle, the tying head and the clutch, as shown by the length of string 20' in Fig. 12. The tension on the string 20' causes it to be drawn into clamped engagement with the initial coating edges of the fingers 60 and 61, so that it is held firmly thereby. When the tying operation, except for the knot stripping action, has been completed, as hereinafter described, a cam projection 80 on the combination cam and gear wheel 15 will have moved into engagement with the roller 74 and effected a rearward tilting of the clutch mechanism frame 71 and a consequent rearward rocking of the finger 61 relative to and in engagement with the fingers 60 to further engage the portion 20' of the string with the clutch. This engagement of the clutch constitutes the anchorage for the portion 20' of the string when the feed needle has swung back to its raised, at-rest position, preparatory to another bundle wrapping and tying operation of the machine. As the tying and clutch mechanisms A and B swing back to the position shown in Fig. 4, which occurs after the initial tying of the knot and during the knot stripping operation, the two lengths of strings 20 and 20' between the tying head and clutch swing into engagement with and are severed by a stationary knife 76 (Figs. 7, 9 and 19). When the strings have been thus severed, the compression of the spring 68 is relieved, and such spring acts to move the clutch parts to the left to their normal positions.

As the clutch finger 61 nears the limit of its intended rearward rocking movement, which is less than that of the rocker frame 71, the rear end of the shaft 70, which is projected rearwardly beyond the frame, strikes an obstruction 77 on the machine frame 1 and returns said rocker frame and finger 61 to their normal positions relative to the fingers 60.

Tying mechanism

The knot tying mechanism A, as shown in Figs. 4 to 10, includes a rocker frame 66 that is mounted for limited backward and forward rocking movements on a shaft 85 suitably mounted in the main frame 1, and disposed below the plane of the rock-shaft 72 of the clutch mechanism. An upright shaft 86 is journaled in the frame 66 and carries a mutilated pinion 87 within the frame and a knot tying head C at its upper end above the frame and for turning movements with the shaft.

The head C includes an upper stationary jaw

88 and a lower movable jaw 89 cooperating to form a bill, with the former providing an inclined shoulder 90 at its under side in advance of the free clamping end of the lower jaw. The incline of the shoulder 90 is downwardly and forwardly from a vertical plane when the head C is in the upright position shown in Fig. 5, and the clamping end of the lower jaw is complementary to this. The purpose of this is to hold the string in engagement with the head until a predetermined knot tying tension has been applied thereto and the head is tilted a predetermined extent relative to the direction of pull of the string to facilitate release of the string from the head, as hereinafter more fully described.

The movable jaw 89 is pivoted to the head for rocking movements about an axis 91, and its rear or tail end extends downward and carries a roller 92 which, when the head is rotated, travels around a stationary cam 93 on the top of the frame 66 and coacts therewith to impart an opening movement to the jaw. The lobe portion of the cam is indicated at 93^a and is positioned so that the jaw is not opened until the head has made approximately three-quarters of a turn, as indicated in Fig. 15, and the jaw then remains open until the head has nearly completed its turn or cycle. The jaw in closing grips and holds the two end lengths 20 and 20' of the string, which are held by and extend from the clutch B. This tying action, except for the particular manner of holding the strings in engagement with the jaws, is common to machines of this character and need not, therefore, be more fully described.

When the jaw 89 has been closed against the jaw 88 to clamp the engaged strings, the roller 92 will have moved into engagement with the upper end portion of a rocker arm 94, which is pressed forward by a spring 95 to exert a yielding closing string gripping action on the jaw. The arm 94 is pivoted at 96 to the rear side of the frame 66. The tension of the spring 95 is varied by a turning of the screw 98 on which it is mounted.

The turning of the tying head shaft 86 is effected at a predetermined point in a rotation of the cam 15 by the engagement of a gear segment 100 thereon with the pinion 87. When the head has been given a complete turn, the gear segment 100 will have passed from engagement with the pinion and a segmental flat flange surface 101 on the cam will then move into locking engagement with a registering flat surface 87^a on the pinion, and this locking action continues until the gear segment again moves into turning register with the pinion in the next cycle of operations of the machine. When the head has completed a turn a shoulder 87^b on the hub of the pinion 87 is engaged by a spring pressed finger 87^c (Fig. 5A) to prevent back turning. This finger is mounted for limited rocking movements to permit the shoulder 87^b to pass it during forward turning.

The frame 66 has an arm 103 projecting forwardly from its lower end and cooperating therewith to form a bell-crank form of lever, the fulcrum of which is the shaft 85. The arm carries a roller 104 that travels in a camway 105 on the inner or rear face of the cam-gear 15. As the outwardly extending or bulged portion of the cam portion 105 passes the roller 104, which is timed to take place after a complete knot forming turning of the head C, the frame 66 is rocked

rearward from the upright position shown in Fig. 5 to and beyond the partial rearwardly inclined position shown in Fig. 8. During this rocking action a pair of opposing knot stripping fingers

5 110 act on the formed knot to peel or force it from the bill of the tying head except for the loop d (Fig. 18) thereof, which is clamped to the jaw 88 at the inner end of the inclined shoulder 90 by the jaw 89 and held until the rocking action

10 has been nearly completed.

The two fingers 110 are pivoted to the under side of the table 1, with a finger disposed at each side of the tying head and extending forwardly from its pivot, as best shown in Figs. 7 and 8.

15 Each of these fingers is urged inward toward the bill of the tying head by a spring 111, and when the tying mechanism is in upright position, as shown in Figs. 5 and 7, are held spaced from the head and in substantially parallel relation

20 to each other by the coaction therewith of spaced rollers 112, which, in the present instance, are carried at the upper end of the pressure arm 94. Inasmuch as the arm 94 has rocking movements with the frame 66, it is apparent that the

25 rollers 112 will be positively swung rearward from spacing engagement with the fingers 110 when the tying head is rocked rearwardly, thus permitting the nose or stripping ends of the fingers 110 to swing inward under the action of

30 their tension springs into engagement with the respective sides of the tying head at the rear of the formed knot thereon. The rollers 112 pass from spreading engagement with the side of the head immediately after the head starts its rearward movement and the fingers 110 then continue in knot stripping positions until the head

35 has completed such movement. When the rearward swing of the tying head has been nearly completed, the forward ends of the fingers will stand a distance in advance of the head bill in the positions relative thereto substantially as illustrated in Figs. 18 and 19. As the formed knot

40 is peeled from the head bill by the action of the fingers 110, the looped portion d of the string, which is engaged to the inclined shoulder of the jaw 88, continues to be held thereby until the portion of the knot around the bill has been peeled or rolled therefrom along the portion d. In so doing, the knot is pushed toward the bundle and caused to be tightened on the portions 45 20 and 20' of the string extending therefrom.

45 This tightening action of the knot on the string is one of the important features of the present invention as it not only strips the knot from the head bill but also tends to slide the knot up along the string portions 20 and 20' and to tighten it against the bundle rather than permitting it to be drawn tight by the expansive action of the bundle after the tying has been completed by the machine and the bundle released, as has heretofore been the case. A loosening of the string with respect to the bundle by the knot tightening action is, therefore, avoided.

55 60 It is apparent that as the knot is tightened by the action of the fingers 110, the tying head continues to rock rearward, thus reducing the angle of the loop holding shoulder 90 of the jaw 88 to the line of pull on the loop d, so that the jaw 89 will open against the tension of the spring

from the knot is not released from the head jaws until a predetermined tightening pressure is applied to the knot by the stripper fingers 110, and that such pressure is determined by the tension exerted by the spring 65 against the pressure arm 84 and the cooperating action of the incline 88, and these are conjointly gauged to release the string from the jaws before the tying head has completely reached its rearwardly rocked position.

Before completing a bundle tying cycle of the machine, the high point in the camway 105 passes from engagement with the roller 104, so that the tying mechanism A is returned to its forward upright position, as shown in Fig. 5, preparatory for the next tying operation.

The timing of the various string clutching and tying operations in a cycle, as determined by the member 15 in its illustrative arrangement of parts, and which operations are effected in a single complete turn of said member, is as follows: Looking at the outer side of the member 15 (Fig. 2), it turns in clockwise direction and its at-rest position is as shown. As the member starts its revolution, it turns approximately 160° with the registering portion of the locking rim 101 in locking engagement with the flat 87a on the tying head pinion 87. Said rim then releases the pinion, and the drive gear segment 100, which is approximately 50° long, moves into mesh with and imparts a complete turn to the head to form the knot thereon. The rim 101 then again engages the flat of the pinion and holds the head against turning for the remainder of the cycle. Upon completing a turning of the head, the roller 104 begins traveling up the bulge of the camway 105 and starts the rearward rocking of the tying head, which movement is completed when the member 15 has advanced approximately 78° from head turning position. During the remainder of the cycle, the head is returned to its upright position. Approximately coincident with the completion of the turning of the head, the cam 80 on the member 15 will engage the roller 74 and effect a rearward rocking of the clutch mechanism frame 71 and the clutch finger 61.

Inasmuch as the member 15 and the needle actuating crank 34 are on the same shaft, it is apparent that the feeding stroke of the needle will take place approximately during the first half of turning movement of the member 15 and that the retracting stroke of the needle will take place during the last half of such movement. It is also apparent that the cam 80 will engage the roller 74 and effect a rearward rocking of the frame 71 and clutch finger 61 approximately coincident with the engaging of the rack or gear teeth 100 with the head turning pinion. Both end portions of the wrapping string will thus be firmly held by the clutch during the knot-tying action, so that a shortening of the string portions between the clutch and the tying head by the wrapping of the string around the tying head during the knot-forming operation will pull the clutch fingers 60 and 61 toward the tying mechanism against the tension of the spring 68. The severing of the string ends between the clutch and tying mechanisms takes place as the strings are rocked into engagement with the knife 76 during the rearward rocking of the tying mechanism A after the forming of the knot about the head has been completed.

Bundle holding means

The bundle holding means includes one or

more pressure feet 115 (Figs. 2 and 3) carried by arms 116 projecting from vertically reciprocating rods 117 which are normally held in raised position by contractile springs 118. A strap 119 extends from each rod 117 downwardly around a sheave 120 in the lower portion of the frame 1, and thence connects through a contractile spring 121 to one arm of a lever 122 mounted on a shaft 123. The other arm of the lever carries a roller 124 which travels on the periphery of the cam 18 that rotates with the shaft 10. This cam is designed to lower the pressure feet into engagement with the bundle at the initial portion of a cycle of operations and to continue the clamping action until the tying of the bundle has been completed. Nothing novel is claimed for this bundle holding mechanism.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. In a bundle tying machine, a rotatable and tilttable tying head having stationary and movable jaws, the stationary jaw having an inclined shoulder in advance of the free end of the movable jaw and cooperating therewith to grip and hold a portion of the knot string when a formed knot is stripped from the head bill, said shoulder being inclined to the line of stripping force applied to the knot with the angle of inclination to said force line diminishing as the head is tilted away from its knot forming position whereby the holding force of the jaws on an engaged string diminishes with the tilting movement.
2. In a bundle tying machine, a rotatable and tilttable tying head having a stationary jaw and a movable jaw yieldingly closing thereagainst to grip the string of a knot being tied, said stationary jaw having an inclined shoulder cooperating with the nose of the movable jaw to hold an engaged string against release from the head, yielding tension means for the movable jaw to hold it closed, said shoulder and tension means cooperating to cause the string to be held by the jaws against a releasing force until the head has been tilted a predetermined extent back from forming position to lessen the angle of inclination of said shoulder to the line of said force.
3. In a bundle tying machine, a rotatable and tilttable tying head including fixed and movable string clamping jaws, means serving to yieldingly hold the jaws closed when the head is in knot stripping position, means operable to strip a formed knot from the head bill and while an anchoring portion of the string is still engaged by the jaws and to tighten the knot on said portion away from the head lengthwise of its bill, said fixed jaw having a clamping shoulder which is inclined outwardly therefrom in the direction of pull on the clamped string portion whereby the force necessary to release said portion from the head jaws diminishes as the head is rearwardly tilted and becomes effective before the head has reached the limit of said tilt.
4. In a bundle tying machine, a pair of opposed stripper fingers pivotally mounted for swinging movements of their free ends toward and away from each other, means yieldingly urging movements of said fingers toward each other, a tilttable and rotatable tying head between said fingers, means tilttable with the head and acting on the

fingers to hold them outwardly from the head when in one position and permitting the fingers to move inwardly against the head bill when the head is initially tilted from such position and to strip a formed knot therefrom and tighten it along a head gripped portion of the knot string as the head continues its tilting movement, and means operable to tilt the head.

5. In a bundle tying machine, a rotatable and tiltable knot tying head having fixed and movable jaws forming a bill, the fixed jaw having an inclined shoulder in advance of the end of the other jaw and cooperating therewith to hold a portion of a knot string engaged with the head bill, said incline being outwardly from the inner surface of its jaw whereby a knot stripping force applied lengthwise of the bill will tend to slide the held string portion outwardly on said incline, and means yieldingly holding the movable jaw closed and cooperating with said shoulder to prevent slipping of the string from the shoulder until the head has been tilted rearwardly a predetermined extent to reduce said angle of inclination relative to the line of applied force and until a predetermined opening pressure has been applied by said force to the movable jaw.

6. In a bundle tying machine having a rocker frame, means for rocking the frame, and a knot tying means carried by and rotatable with the frame, a string clutch mechanism including 10 yieldingly spaced clutch members anchored to said rocker frame for rocking movements therewith and yieldingly movable toward and away from the knot tying means lengthwise of a gripped string being tied, a companion clutch member carried by said frame for rocking movements therewith and for independent rocking

movements in a plane transverse to the string and to cooperate with said first members to clutch a string while being tied, and means operable to rock said companion clutch member relative to the frame and said first clutch members to grip a string to the latter in predetermined relation to a tying operation.

7. In a bundle tying machine having a rocker frame, means for rocking the frame, and a head 15 tying means carried by and rockable with the frame, a string clutch means carried by said frame and rockable therewith, said clutch means including a pair of clutch fingers anchored to the frame to rock therewith, a companion clutch finger carried by said frame and rockable relative thereto transverse to its rocking axis to clutch to said pair of fingers a string to be tied, all of said fingers being rockable together relative to the frame toward and away from the tying means, means yieldingly resisting said movement of the fingers toward the tying means, and means for rocking said companion finger in predetermined relation to a rocking of the said frame.

8. In a bundle tying machine including a tiltable and rotatable tying head having a bill with string gripping jaws, a pair of opposed stripper fingers mounted for movements toward and away from each other with said bill disposed therebetween, whereby the fingers may engage and strip a knot from the bill during a predetermined tilting movement of the tying head, and means operable to move the fingers out of knot stripping position during predetermined portions of the 20 head tilting movements.

ALBERT H. SAXTON.
